TICKET CASE

Filed April 20, 1921

Walter Johnson
INVENTOR.

UNITED STATES PATENT OFFICE.

WALTER J. SCHRAMM, OF CHICAGO, ILLINOIS.

TICKET CASE.

Application filed April 20, 1921. Serial No. 462,828.

My invention relates to improvements in ticket cases, and has for its object the production of a device in which separable compartments are used, and from which the ticket can be withdrawn without requiring the use of springs or weights of any kind.

A further object is the production of a device that can be used in spaces below the counter, and one in which the ticket always 10 is visible.

A further object is the production of a device of simple construction, one that can be manufactured cheaply, and one not liable to disarrangement of parts.

15 These and such other objects as may appear hereinafter are attained by my device, an embodiment of which is illustrated in the accompanying drawings, in which—

Figure 1 represents a perspective view of 20 a portion of a ticket cabinet equipped with my special device;

Fig. 2 is a side view of a tube in place;

Fig. 3 is a perspective view showing the bottom of my device; and

25 Fig. 4 is a plan view of the blank from which the device is formed.

Like numerals of reference indicate like parts in the several figures of the drawing.

Referring now to the drawings,—5 represents a ticket case having a bottom shelf 6. At the end of the shelf, a metallic angular strip 7 is placed, bent forwardly, as shown at 8, leaving a space 9 between the under surface of the flange 8 and the upper surface of 35 the shelf 6.

The ticket receptacle or tube is formed preferably from a single sheet of tin or like metal, as shown in Fig. 4, having a bottom 10, a continuous side wall 11, an interrupted 40 side wall 12, and internally projecting flanges on either side, designated as 13. The front portion is cut away, as shown at 14, and flanges 15, 15, are formed, designed to be bent inwardly, as shown in Figs. 1 and 3, 45 holding the tickets 16 in place.

A notch 17 is cut out of the metal, as shown in Fig. 4; the extreme end of the flange 13, indicated as 18, is bent downwardly and rearwardly, forming a stop for 50 the top ticket 19, shown in Fig. 1. A spring 20, is secured to the bottom of the tube at 21, serving to hold the tube securely in place when pushed in, the lip 22 fitting under the flange 8 into the slot or groove 9.

The tickets 16 are placed in the tube, the 55 upper portion of the tube being open, as shown in Figs. 1 and 2, the tickets being slanted downwardly, lying at a rather obtuse angle, so that they can be pulled forwardly readily by the finger of the operator. 60 The last ticket, shown as 19, is placed on top, under the flange, and held in place by the stop 18, and the groove 17 leaves a clear way for the passage of but a single ticket, so that it is impossible to pull out more than one 65 ticket at a time.

By the use of this device, all spring means heretofore employed to keep the ticket pressed forwardly are eliminated; also the use of the balls or marbles. In the use of 70 the balls or marbles, when the last ticket is pulled out, the marble frequently drops out on the floor and is lost, as there is no means of knowing when the last ticket is reached; whereas in my device, the last ticket, lying on 75 top in plain view, as the tickets are gradually used up, will sag down, giving warning to the user that the supply is nearly exhausted. In all other devices, the ticket is pulled out from the bottom, making it very inconvenient in cases where it is necessary to put the ticket case below the level of the waist. By 80 the use of my device, however, in which the ticket is pulled forwardly, the case can be below the counter, or at any level desired. 85

The device is formed, preferably, of tin or metal of some kind, and is manufactured easily from a single blank, with few operations. It is easy to install, and once installed is easily removed for filling, and easily put back in place. 90

I am aware that while I have shown certain embodiments of my invention, other forms may be utilized which will accomplish the same result, without departing from the 95 spirit of my invention.

Having thus described my invention, I claim—

A ticket case including a supporting frame, a plurality of rectangular ticket tubes 100 carried thereby at an angle inclined sufficiently so that a stack of tickets placed in a tube will feed downwardly by gravity without the use of weights or the like, the lower ends of the tubes being provided with bottom flanges to hold the tickets substantially horizontal and with a slot through which the lowermost ticket may be drawn forwardly, 105

and means for holding a designating ticket on the top side of the lower end inside of each tube by the tickets in the tube whereby the designations are discernible with the 5 tubes mounted closely one above the other, and whereby said designating tickets tilt downwardly at the rear end as the stacks

decrease sufficiently below the top of the designating ticket to indicate that refilling is required.

10

In witness whereof I have hereunto subscribed my name.

WALTER J. SCHRAMM.
